UNITED STATES PATENT OFFICE.

RENE CHARLES WATTELLIER, OF SAMOIS-SUR-SEINE, FRANCE.

FUEL ECONOMIZER FOR EXPLOSION ENGINES.

Application filed June 8, 1921. Serial No. 475,931.

To all whom it may concern:

Be it known that I, RENÉ CHARLES WATTELLIER, citizen of the French Republic, residing at Samois-sur-Seine, Seine and 5 Marne, in the Republic of France, have invented new and useful Improvements in Fuel Economizers for Explosion Engines, of which the following is a specification.

This invention relates to a fuel economizer 10 for explosion engines, by means of which an amount of air may be automatically introduced into the intake pipe of the engine at a point between the throttle and the admission valve at the same time as the 15 throttle is opened and in proportion to the extent of the opening movement of the latter, whereby a better utilization of the charge is obtained and consequently an economy is realized in the fuel consumption 20 of the carburetter.

A characteristic feature of this economizer resides in that it comprises a casing adapted to be mounted on the intake pipe of the engine at a point between the throttle 25 and the admission valve, said casing being provided with an air passage which is controlled by a rotatable disc plate provided with a port and connected by a flexible transmission to a member controlling the 30 throttle.

Other features of the invention will appear from the following description.

In the accompanying drawings given by way of example:

35 Fig. 1 is a section through the axis of the fuel economizer constructed in accordance with the present invention.

Fig. 2 is a plan view of the same, the carburetter being removed.

40 Fig. 3 is a plan view.

Fig. 4 shows the apparatus mounted on the intake pipe of an engine.

Fig. 5 is an axial section corresponding 45 to Fig. 1 and showing a modified construction.

Fig. 6 is a diagrammatic view of the economizer together with the controlling members for the same.

As shown in Figs. 1 to 4, the apparatus 50 comprises a casing 1 provided with a screw-threaded tubular projection 5^a by means of which it is secured to a neck 6 (Fig. 4) provided on the intake pipe 7 of the engine at a point between the throttle 23 and the admission valve not shown. A nut 8 ensures the fixation. The bottom wall 4 of

the casing is provided with a hole 5 which extends through the tubular projection 5^a and through which the air will pass into the intake pipe 7. The casing 1 is provided with a flat recess 9 in which a disc plate or obturator 2 is rotatably supported. The bottom wall of said recess 9 may be provided with shallow arcuate recesses 10. Upon the casing, is secured by means of 60 screws 11, a cover 12 provided with holes 13 for the inlet of air and carrying a boss 14 in which the end of a flexible transmission 15 is guided.

The disc plate 2 is mounted on a central 70 screw or pivot 16 supported by the bottom 4 of the casing. Through the disc plate extends an oblong or wedge-shaped, designed opening 17 (Fig. 2) which is adapted to register with a hole 5 of the casing when 75 the plate 2 is oscillated, and will coincide with said hole in the opened position of the apparatus. The disc plate is carefully dressed in order to ensure a tight joint and it is constantly urged to its closing position by a spring blade 18 secured to an arm 19 which is itself secured to the disc plate, said spring blade bearing upon a stud 20 secured to the cover 12. A yielding spider 21, with four branches, held by the screws 80 11 bears, at its central part, upon the head of the central screw 16, and holds the disc plate 2 in contact with the bottom of the casing 1. To the lever 19, is secured the controlling flexible wire within the tube 15, 85 said wire being connected at its other end to the lever 22 (Fig. 4) operating the throttle 23 of the carburetter. The lever 19 moves in a notch formed in the upper edge 24 of the casing.

A supporting yoke 3 secured to the casing 1 carries an oscillating lever 25 by means of which the lever 19 may be locked in the closing position of the disc plate; said lever is actuated by means of a flexible wire within the tube 26, said wire being secured to the tail part 27 of the lever 25 and connected at its other end to an operating knob 28.

The operation of the apparatus is as follows:

At rest, i. e., in the closing position, the passage 5 of the casing 1 is closed by the disc plate or obturator 2. When the accelerator is depressed, the disc plate 2 which 110 is then actuated by the lever 22 of the throttle 23 through the medium of the flexible

2
cable 15 and the lever 19, is turned in the direction of the arrows (Fig. 2), so that its lengthened opening 17 comes over the passage 5 of the casing 1, whereby an amount of air is introduced into the intake pipe in proportion as the passage 5 is uncovered and the throttle 23 is opened.

5 In the modified construction shown in Figs. 5 and 6, the casing *a* of the economizer 10 is closed by a plate *d* carrying a screw-threaded tubular projection *d'* through which a passage *j* extends. Said projection carries a nut *e* and a washer *f* and is used as in the above construction for the purpose 15 of securing the apparatus upon the intake pipe of the engine.

Upon the bottom plate *d* of the casing, is 20 rotatably mounted the rotatable disc plate or obturator *h* which is carefully dressed and pressed upon the plate *d* by a coil 25 spring *g*.

The disc plate *h* is provided with an oblong opening *m* which may coincide with the circular passage *j*. It is actuated by a 30 flexible cable *k* which passes through a guide *n* and is connected to the accelerator or other member controlling the throttle of the engine. A spiral spring *i* tends to bring the disc plate *h* to its closing position. By 35 means of said arrangement, an additional air inlet may be obtained into the intake pipe as the throttle is opened, as described above.

According to this modified construction, 35 the apparatus is also provided with a device whereby the angular position of the disc plate *h* in the casing may be varied at any instant, so as to change the amount of air drawn in, independently of the action of the member controlling the throttle. For 40 this purpose, the operating cable *k* passes around a guide pulley *c* having a fixed axis and a tightening pulley *l*. The pulley *l* is carried by a yoke member *b* which is 45 pivoted on the shaft of the pulley *c*. The yoke *b* may be angularly displaced in the direction of the arrow (Fig. 6) by means of a flexible cable *p* operated by a handle *q* secured either to the steering wheel or to 50 the dash board of the vehicle. The pulley *l* can thus be bodily displaced around the axis of the pulley *c*. It will thus act to tighten the cable *k*, whereby a rotary movement will be imparted to the disc plate *h*. By this 55 means, the passage offered to the air through the hole *j* and the opening *m* when the cable *k* is pulled will be increased. The opening *m* has such dimensions that the operation of the engine will be rendered most flexible 60 an amount of air proportional to the charge drawn in being introduced for each speed of the engine. By means of the handle *q* and whatever the working conditions of the engine may be, the driver is thus enabled to

bring the opening *m* in the disc plate *h* 65 to the necessary distance from the hole *j*, the apparatus continuing to act thereafter automatically. Means are thus provided for adjusting the amount of air necessary to the engine in an instantaneous and easy 70 manner.

It will be seen that the purpose of the apparatus is to obtain an economy of fuel and also to increase the flexibility and power 75 of the engine. In addition thereto it enables to use with the same engine different fuels such as gasoline, benzol, paraffin or spirit, an instantaneous adjustment being possible.

The invention is not limited of course to 80 the constructive arrangements shown or described. For instance, the tightening pulley *l* might be replaced by any other suitable tightening device.

Having now described my invention, what 85 I claim as new and desire to secure by Letters Patent is:

1. A fuel economizer for explosion engines comprising a casing, an eccentrical tubular projection on said casing adapted 90 to be secured to the intake pipe of the engine and connecting the capacity of the casing to the said intake pipe, means for admitting outer air into said casing, a rotatable disc plate in the casing provided with a 95 port registering with the inlet of said tubular projection, a flexible transmission for operatively connecting said disc plate to a member controlling the throttle of the engine and means for producing a bend in said flexible transmission and thereby displace angularly the disc plate independently of the action of the throttle valve actuating member.

2. A fuel economizer for explosion engines comprising a casing, an eccentrical tubular projection on said casing adapted 100 to be secured to the intake pipe of the engine and connecting the capacity of the casing to the said intake pipe, means for admitting outer air into said casing, a rotatable disc plate in the casing provided with a port 105 registering with the inlet of said tubular projection, a flexible transmission for operatively connecting said disc plate to a member controlling the throttle of the engine, a guide pulley for said flexible transmission, a 110 stationary shaft for said guide pulley, a yoke pivotally mounted on said shaft, a second guide pulley carried by said yoke 115 and means for displacing the yoke angularly so as to stretch the flexible transmission and angularly displace the said disc plate independently of the action of the 120 throttle valve actuating means.

In testimony whereof I have signed my name to this specification.

RENÉ CHARLES WATTELLIER.
